UNITED STATES PATENT OFFICE.

BYRON C. RIBLET, OF NEW YORK, N. Y.

GRIP FOR TRAMWAY BUCKET CONVEYERS.

953,763.

Specification of Letters Patent.

Patented Apr. 5, 1910.

Application filed August 4, 1909. Serial No. 511,125.

To all whom it may concern:

Be it known that I, BYRON C. RIBLET, a citizen of the United States, and residing in the city of New York, county and State 5 of New York, have invented certain new and useful Improvements in Grips for Tramway Bucket Conveyers, of which the following is a specification.

In the operation of tramway bucket conveyor systems, in which the load carrying bucket is mounted upon a hanger suspended from a car running upon a cable or other track, and in which the propelling rope or cable is detachably coupled to the hanger 10 frame beneath the car, it is necessary, because of the varying elevations over which the bucket travels, to provide a gripping device between the hanger frame and the conveying rope or cable which will permit 15 relative movement between the hanger frame and grip, so that the bucket may hang approximately vertically no matter at what angle the tramway track and propelling rope or cable are presented. It is common 20 in this art to provide such a grip in which the bucket hanger turns or pivots freely upon the grip supporting frame.

My present invention relates to an improvement upon this style of conveyer grip. 30 The main object of my present invention is to provide a simple and substantial grip mechanism in which the two members of the grip are carried by a grip ring rotatably mounted within the bucket hanger 35 in such manner that the jaws will be presented approximately in line with the center of rotation of the grip carrying ring within the bucket hanger.

My invention also includes grip operating 40 mechanism mounted upon the bucket hanger and engaging the cable grip at a point or points approximately in line with the center of rotation of the grip carrying ring. With this arrangement, it will be clear that 45 the turning movements of the bucket hanger on the grip carrying ring, being approximately concentric with the line upon which the grip engages the cable and the operating means engage the grip, the oscillating movements of the bucket and hanger in traveling 50 from point to point will not interfere with the closed or clamped position of the grip and will not subject the conveying rope or cable to undue transverse strain at the point 55 of engagement of the grip.

In the operation of my improved grip

ping mechanism, the grip and operating means turn relatively at their point or points of engagement in the same axis that the bucket hanger swings.

Numerous modifications embodying the essential features of my present invention can be employed. In the several modifications so far developed by me, as hereinafter described, I have arranged the two relatively movable parts of the grip upon the grip carrying ring with anti-friction rollers having transversely curved peripheries,—constituting in effect zones of spheres,—having their longest diameters arranged in 60 the plane of the axis upon which the bucket hanger rotates with relation to the grip carrying ring, and grip operating means upon the bucket hanger, preferably in the form of a wedging device, which is adapted to 65 be presented between the anti-friction rollers of the grip members for operating the grip. This arrangement is such that the points of engagement between the wedging device and the anti-friction rollers of the 70 grip members will be approximately in line with the axis of relative rotation between the hanger and grip carrying ring. By reason of the formation of the anti-friction rollers, it will be observed that there will 75 be a single point of contact between the wedging device and each roller so that in the relative movements between the bucket hanger and grip ring, the friction between the wedging device and anti-friction rollers 80 of the grip members will be reduced to a minimum, and such relative movement will 85 not affect the clamped condition of the grip.

In addition to these main features, my invention includes other important structural features and in order that my invention may be fully understood I will first describe the same with reference to the accompanying drawings, and afterward point out the novelty more particularly in the annexed claims.

In said drawings: Figure 1 is a detail side elevation of part of a tramway bucket conveyer showing my improved grip applied thereto. Fig. 2 is a vertical transverse, sectional elevation of the same. Fig. 3 is an enlarged vertical sectional view of the preferred form of grip and operating mechanism. Fig. 4 is a detail front elevation of the parts of the mechanism shown 105 in Fig. 3. Fig. 5 is a detail vertical sectional view of the gripping members taken

on the section line $x-x$ of Fig. 3. Fig. 6 is a view similar to Fig. 3 of a modified form of my invention. Fig. 7 is a detail side elevation of the same. Fig. 8 is a detail plan view of the form of wedge shown in Fig. 6. Fig. 9 is a detail side elevation of a further modification. Fig. 10 is a vertical transverse sectional elevation of the form of mechanism shown in Fig. 9 and Fig. 11 is a detail side elevation of the stationary cam track employed for operating the grip in the form shown in Figs. 9 and 10.

Tramway conveyers of the type to which my present improvements relate, include a tramway track bar or rope, such as indicated at 1, a wheeled carriage indicated at 2, a bucket supporting or hanger frame indicated at 3, suspended from a pivotal connection with the carriage 2 as indicated at 4, a bucket 5 pivotally mounted at 6 in the lower ends of the arms of the hanger frame 3, dogs 7 pivoted to the hanger frame at 8 and engaging lugs 9 upon the bucket to sustain the bucket in carrying position, and a propelling or conveying rope or cable indicated at 10 to which the bucket hanger is detachably coupled through means of a suitable gripping device carried by the hanger frame. As stated above my present invention relates to improvements in this gripping device. The bucket hanger frame 3 supports by means of arms or braces 15 or other suitable connection a circular bearing shell 20 within which is freely journaled the grip carrying ring 25. This bearing 20 and ring 25 may be of any suitable construction, such as now commonly used in this art. As shown in the drawings, the ring 25 is shaped like a hollow pulley with the strengthening end wall 26 formed with a central horizontal slot 27 for the reception of the movable grip member.

30 is the fixed or rigid grip member formed integral with or otherwise securely fastened to the end wall 26 of the grip carrying ring 25. This fixed grip member 30 is in the form of a shallow hook adapted to fit over the propelling cable 10.

35 is the movable grip member which is movably mounted in the guide slot 27 and is formed with the grip jaw 36 which is adapted to engage the conveying rope 10 and clamp it rigidly against the fixed grip member 30. The movable grip member is also formed with the laterally projecting guide lugs 37 which engage and slide in the guide slots 38 formed in the side checks or plates 39 extending downwardly from the fixed hook 30 and outwardly from the end plate 26 of ring 25. The movable grip member 35 has the rearwardly presented separated bearing arms 40 in which is journaled a vertical pin 41 having freely mounted upon it an anti-friction roller 42. This anti-friction roller 42 is supported in the space

between the bearing arms 40 and is free to rotate upon the vertical pin 41. The lower end of the pin 41 projects beyond the bearing arm of grip member 35 and guides in a slot 45^a cut in the central guide wall 45 of the ring 25. Projecting from the lower bearing arm 40 is a grip releasing hook or lug 46 operating as hereinafter explained.

Formed integral with or otherwise rigidly secured to the bearing ring 25 is the rearwardly presented bracket 50 formed with a slot 51 in its rear wall to receive the anti-friction roller 52, which is freely journaled upon a bearing pin 53 mounted in the upper and lower walls of the slotted bracket 50.

It will be observed that the anti-friction rollers 42 and 52 mounted upon the movable and fixed members of the grip (the roller 52 is in effect mounted upon the fixed member of the grip because both the bracket 50 and grip member 30 are rigid with the ring 25) have their peripheries rounded or curved transversely making them in effect in the shape of zones of spheres. The arrangement of these rollers is such that their longest diameters, including the highest parts of their peripheries, will be presented in a plane which includes the axis upon which the bearing 20 and grip ring 25 have relative rotary movement. It will also be observed that the engagement of the grip members with the conveying cable is also approximately in the same plane.

60 is an overhanging bracket projecting from the bearing frame 20, and 65 is an operating shaft freely journaled in the depending arms 61 and 62 of the bracket 60. This shaft 65 carries between the arms 61 and 62 a wedging cam or disk 70. The shaft 65 is supported just above the anti-friction rollers 42 and 52, and the wedging member 70 upon said shaft 65 projects between said rollers 42 and 52 and engages each roller at a single point in the axial line of relative motion between bearing 20 and ring 25. The outer end of the shaft 65 carries a heavy operating arm 75 in the outer end of which is freely pivoted a combined weight and anti-friction roller 76. Adjacent to the track bar 1 at any suitable point at which it is desired to disengage the grip from the conveying cable, is mounted an inclined cam track 80 in proper position to engage the weight or roller 76 as the car and bucket hanger move toward it, with the result that the shaft 65 will be turned in its bearings to rotate the wedging member 70 to release the grip. The wedging member 70 also carries a cam flange 71 which projects into engagement with the lug or hook 46 upon the movable grip member 35 so that upon backward movement of the wedge between the rollers 42 and 52, the cam flange 71 will engage the lug or hook 46 and positively move the grip member 35 away from the grip

member 30 to permit the disengagement of the grip from the cable.

Since the point of engagement between the cam flange 71 and hook 46 is slightly below the axial line of relative motion between bearing 20 and ring 25, it is necessary to provide for sufficient clearance between flange 71 and hook 46 in order that the swinging of the bucket hanger upon the grip ring will not be interfered with by the engagement of flange 71 with hook 46.

In Figs. 6, 7 and 8, I have shown a modified form of my improved gripping device in which a straight wedge is employed in place of the rotary wedge shown in the preferred form. In this modification, the main parts of the grip are the same as above described and are identified by the same reference numerals. A straight bar-shaped wedge 85 is presented in horizontal position between the anti-friction rollers 42 and 52 and guided in suitable bearings indicated at 86 formed in the flange extensions of bearing frame 20. This wedging member 85 has upon its upper face a rack bar 87 with which engages a gear wheel 88 keyed to the shaft 65 which is journaled in the bracket frame 60 and operated in the same manner as above described. The hook or lug 46 upon the movably clamped member 35 is engaged by a cam flange 89 to draw the movable clamp member rearwardly when the wedge is moved backwardly between the anti-friction rollers of the clamp. It will be understood that this clamp operating wedge in this modified form is actuated in the same manner as the rotary form of wedge above referred to. The points of engagement between the wedge and the high portions of rollers 42 and 52 are in the axial line of relative rotation between bearing member 20 and ring member 25, the same as in the preferred form.

In Figs. 9, 10 and 11, I show a further modification in which the clamping members are constructed exactly as in the preferred form, and in which a bar form of wedge is employed for operating the clamp. In the drawings of this form I have also employed the same reference numerals to indicate parts constructed the same as in the preferred form.

90 is a bar-shaped wedge extending vertically across the rear face of the grip ring 25 and passing through suitable guide brackets 91 and 92 extending rearwardly from the bearing frame 20 of the bucket hanger. The wedge 90 engages the anti-friction rollers 42^a and 52^a journaled upon pins 41^a and 53^a in the movable and fixed grip members respectively. The wedge is formed upon each side with a cam flange 93 which engages an inwardly projecting lug or hook 46^a, two of which are formed at the rear end of the movable grip member 35 for

the purpose of effecting the rearward movement of the movable grip member when the clamping pressure is removed. The upper end of the wedge 90 is freely pivoted at 100 to the pair of links or pitmen 101 pivotally connected at 102 with an operating and controlling bell crank lever 105 which is pivotally mounted at 106 between the forwardly projecting ears 107 of the hanger frame 3. This bell crank lever 105 and the links 101 constitute a toggle between the stationary fulcrum 106 and pivot end 100 of the wedge 90. The free end of the bell crank lever 105 carries a ball or weight 110 which tends to straighten the toggle connection with the wedge 90 for effectively applying clamping pressure to the clamp 30—35. Anti-friction rollers 100^a on pin 100 engage guide plate 100^b of frame 3 to reduce friction.

For operating the clamp operating mechanism of this last described modification, it is necessary to provide alongside of the tramway track a spiral form of cam track, such as shown at 115, which cam track must be curved upwardly and inwardly. This shape of cam track is necessary because the operating arm 105 projects out at right angles to the plane of travel of the bucket hanger and in releasing the grip must be moved upwardly in a curved path toward the track bar 1.

It will be observed that in all of the forms of my invention illustrated and described, the points of engagement between the grip operating wedging device and the anti-friction rollers upon the grip members are approximately in line with the axis of relative rotation between the grip ring and bearing of the bucket hanger. As above explained, this permits freedom of movement for the bucket hanger upon the grip ring, without interfering with the tension of the clamp in clamped position. Another important advantage resulting from the use of the clamp operating wedging means is the capacity for gripping different sizes of power cables, it being clear that the wedge will close the jaws of the grip more or less upon the cable to suit the size in use.

While I have limited the illustration of the stationary cam track for operating the wedging means to the use of such track for opening or releasing the grip, I would have it understood that under certain circumstances the grip operating wedging device can be actuated by a similar form of cam track arranged to cause the closing of the grip upon the cable at the start of the conveying operation. This means for automatically clamping the grip may or may not be employed, since it will be clear that it is feasible to actuate the grip operating mechanism by hand. The wedge operating device forms no part of my present invention excepting in a broad sense.

What I claim is:

1. In a mechanism of the character described, the combination with a bucket hanger, and a propelling cable, of a grip ring rotatably mounted in the bucket hanger, a cable grip carried by said ring, and grip operating mechanism mounted upon said hanger and engaging the grip approximately in line with the axis of rotation of said ring in said hanger.
- 5 2. In a mechanism of the character described, the combination with a bucket hanger, and a propelling cable, of a grip ring rotatably mounted in the bucket hanger, a cable grip carried by said ring and adapted 15 to engage said cable approximately in line with the axis of rotation of said ring in said hanger, and grip operating mechanism mounted upon said hanger and engaging the grip approximately in line with said axis.
- 10 3. In a mechanism of the character described, the combination with a bucket hanger, and a propelling cable, of a grip ring rotatably mounted in the bucket hanger, a two-part grip carried by said ring, one 25 part of which is movable relatively to the other, and grip operating mechanism mounted upon said hanger and engaging the movable part of said grip at a point approximately in line with the axis of rotation of said ring within said hanger.
- 20 4. In a mechanism of the character described, the combination with a bucket hanger, and a propelling cable, of a grip ring rotatably mounted in the bucket hanger, a two-part grip carried by said ring, one 35 part of which is movable relatively to the other, and grip operating mechanism mounted upon said hanger and engaging the two parts of said grip at points approximately in line with the axis of rotation of said ring within said hanger.
- 40 5. In a mechanism of the character described, the combination with a bucket hanger, and a propelling cable, of a grip ring rotatably mounted in the bucket hanger, a two-part grip carried by said ring, one 45 part of which is movable relatively to the other, said grip being adapted to engage said cable approximately in line with the axis of rotation of said ring in said hanger, and operating mechanism mounted upon said hanger and engaging said grip approximately in line with said axis.
- 50 6. In a mechanism of the character described, the combination with a bucket hanger, and a propelling cable, of a grip ring rotatably mounted in the bucket hanger, two 55 relatively movable grip members carried by said ring, and grip operating wedging means mounted upon said hanger and engaging the two grip members.
- 60 7. In a mechanism of the character described, the combination with a bucket hanger, and a propelling cable, of a grip
- ring rotatably mounted in the bucket hanger, two relatively movable grip members carried by said ring, and grip operating wedging means mounted upon said hanger and engaging the two grip members 70 at points approximately in line with the axis of rotation of said ring.
8. In a mechanism of the character described, the combination with a bucket hanger, and a propelling cable, of a grip ring rotatably mounted in the bucket hanger, two relatively movable grip members carried by said ring, said grip members being adapted to engage said cable approximately in line with the axis of rotation 80 of said ring in said hanger, and grip operating wedging means mounted upon said hanger and engaging the two grip members at points approximately in line with said axis.
- 85 9. In a mechanism of the character described, the combination with a bucket hanger and a propelling cable, of a grip ring rotatably mounted in the bucket hanger, two relatively movable grip members carried by said ring, and grip operating wedging means mounted upon said hanger and presented between said two grip members and engaging said members at single points approximately in line with the 90 axis of rotation of said ring.
10. In a mechanism of the character described, the combination with a bucket hanger and a propelling cable, of a rotatable grip ring mounted in said hanger, a two-part cable grip mounted upon said ring, one part of which is movable relatively to the other, said grip being adapted to engage said cable at a point approximately in line with the axis of rotation of said ring, and an operating wedge movably mounted upon said hanger and engaging between the two parts of said grip at points approximately in line with the axis of rotation of said ring.
- 100 11. In a mechanism of the character described, the combination with a traveling bucket hanger, and a propelling cable, of a grip ring rotatably mounted in the bucket hanger, a two-part cable grip carried by said ring, a grip operating wedge mounted 110 upon said hanger and engaging the grip at a point approximately in line with the axis of rotation of said ring, a wedge operating shaft journaled in said hanger, an arm mounted upon said shaft, and a stationary cam track adapted to engage said arm for releasing said grip.
- 115 12. In a mechanism of the character described, the combination with a traveling bucket hanger, and a propelling cable, of a grip ring rotatably mounted in the bucket hanger, a two-part cable grip carried by said ring, a grip operating wedge mounted 125 upon said hanger and engaging the grip at a point approximately in line with the axis of rotation of said ring.
- 130

axis of rotation of said ring, a wedge operating shaft journaled in said hanger, a weighted arm mounted upon said shaft, and a stationary cam track adapted to engage 5 said arm for releasing said grip, and means upon said wedge for retracting the movable member of said grip.

13. In a mechanism of the character described, the combination with a bucket 10 hanger and a propelling cable, of a grip ring rotatably mounted in said hanger, a cable grip carried by said ring and comprising two relatively movable parts, a grip operating wedge movably mounted upon 15 said hanger and engaging the two parts of said grip approximately in line with the axis of rotation of said ring, means for operating said wedge, and additional means of engagement between said wedge and the 20 movable part of said grip for opening the grip when the wedge is withdrawn.

14. In a mechanism of the character described, the combination with a bucket hanger and a propelling cable, of a grip 25 ring rotatably mounted in said hanger, a cable grip carried by said ring and comprising two relatively movable parts, a grip operating wedge movably mounted upon said hanger and engaging the two parts of said 30 grip approximately in line with the axis of rotation of said ring, means for operating said wedge, and a cam flange upon said wedge adapted to engage the movable part of said grip for opening the grip when the 35 wedge is withdrawn.

15. In a mechanism of the character described, the combination with a bucket hanger and a propelling cable, of a grip 40 ring rotatably mounted in said hanger, a two-part grip carried by said ring, a rotatable wedging disk journaled upon said hanger and engaging between the two parts 45 of said grip at points approximately in line with the axis of rotation of said ring, and means for operating said wedging disk.

16. In a mechanism of the character described, the combination with a bucket hanger and a propelling cable, of a grip 50 ring rotatably mounted in said hanger, a two-part grip carried by said ring, a rotatable wedging disk journaled upon said hanger and engaging between the two parts 55 of said grip at points approximately in line with the axis of rotation of said ring, means for operating said wedging disk, and a cam flange upon said disk engaging a part upon the movable grip member for opening the grip.

17. In a mechanism of the character described, the combination with a tramway 60 track, a carriage operating upon said track and supporting a bucket hanger, and a propelling rope, of a grip ring rotatably mounted in said hanger, a two-part grip carried by said ring, wedging means mounted upon 65 said hanger engaging the two parts of said grip at points approximately in line with the axis of rotation of said ring, a wedge operating arm suitably connected with said wedge, and a stationary cam track mounted 70 adjacent to said tramway, and adapted to engage said wedge operating arm.

18. In a device of the character described, the combination with a bucket hanger and a propelling cable, of a grip ring rotatably 75 mounted in said hanger, a two-part cable grip mounted upon said ring, one of said parts being movable relatively to the other, anti-friction rollers journaled upon the two parts of said grip, and wedging means 80 mounted upon the hanger and adapted to engage said anti-friction rollers for operating said grip.

19. In a device of the character described, the combination with a bucket hanger and a propelling cable, of a grip ring rotatably 85 mounted in said hanger, a two-part cable grip mounted upon said ring, anti-friction rollers journaled upon the two parts of said grip, each of said rollers being formed with 90 transversely convexed surfaces and arranged with their greatest diameters in the plane of the axis of rotation of said ring, and wedging means mounted upon the hanger and adapted to engage said anti-friction 95 rollers for operating said grip.

20. In a mechanism of the character described, the combination with a bucket hanger, and a propelling cable, of a grip ring carrying a relatively fixed grip member, a movable grip member mounted upon the grip ring, anti-friction rollers journaled upon the fixed and movable grip members, each of said rollers having its periphery 100 shaped in the form of a spherical zone, said 105 rollers being journaled in the plane of the axis of rotation of said ring, and wedging means mounted upon said hanger and engaging the high points of said anti-friction rollers approximately in line with the axis 110 of rotation of said ring.

BYRON C. RIBLET.
